UNITED STATES PATENT OFFICE.

NICHOLAS DARROW, OF HEMPSTEAD, TEXAS.

IMPROVEMENT IN CAR-COUPINGS.

Specification forming part of Letters Patent No. 178,049, dated May 30, 1876; application filed March 6, 1876.

To all whom it may concern:

Be it known that I, NICHOLAS DARROW, of Hempstead, in the county of Waller and State of Texas, have invented a new and Improved Car-Coupling, of which the following is a specification:

In the accompanying drawing, Figure 1 represents a top view, and Fig. 2 a vertical longitudinal section on line *c c*, Fig. 1, of my improved car-coupling.

Similar letters of reference indicate corresponding parts.

The invention consists in combining with draw-heads a spring-buffer on each side of the couplers, constructed as hereinafter described.

In the drawing, A represents the draw-heads of my improved car-coupling, which are made of hook shape, with curved shank pivoted at its rear end to the car-frame. Each draw-head is acted upon, in longitudinal direction, by a spiral spring, *a*, and, in lateral direction, by a band-spring, *b*, the interlocking faces or drawing-surfaces of the draw-heads being provided with cogs or corrugations that give a firm hold to the draw-heads after coupling, and make them less liable to slip and get separated. The hook end of the draw-head is extended above and below the curved shank, to give a wider range of vertical motion for coupling cars with platforms of different height. The extensions or shoulders serve, also, as bumpers, and relieve the follower-plates on rear of draw-bars from too great a strain when brought in contact with cars provided with other draw-heads.

The draw-heads A are uncoupled by a fulcrumed lever, B, that acts, by its front end, on the draw-head, and is connected at its rear end, by a wire rope or chain, to a shaft with hand-wheel pawl-and-ratchet mechanism on the platform, side, or top of car, so that the draw-heads may be readily uncoupled by the brakeman.

The coupling is accomplished automatically, by the action of the draw-heads, on the approach of the cars; the uncoupling, by the hand-wheel or equivalent mechanism, at any time, even without slackening the speed of the cars, both operations being entirely without danger, as no entering between the cars is necessary.

The hook ends of the draw-heads are centrally recessed and vertically perforated, to couple with the common pin-and-link coupling.

The cars are arranged with spring-buffers C, of which the buffers of one car have side-extending guard-plates D, to which the tapering heads of the buffers of the adjoining car are fitted. The guard-plates guide and assist in the coupling of the cars, and also prevent the cars from swinging too much from one side of the track to the other, which wears on the axle-journals, and causes, sometimes, the throwing of the cars off the track.

The spring-acted buffers secure, by their adjustment on passing around curves, the coupling of the draw-heads, so that no accidental disconnection of the same, by violent jerks or short curves, is rendered possible, and a reliable coupling for cars with platforms of even or different heights is furnished.

Having thus described my invention, I claim as new and desire to secure by Letters Patent—

The combination, with draw-heads, of spring-buffers C C, provided with tapering head and plates D, respectively, the same being arranged on both sides of the couplers, as and for the purpose specified.

N. DARROW.
